UNITED STATES PATENT OFFICE.

FRANCIS ALBERT CRESSWELL, OF STRONGSTOWN, PENNSYLVANIA.

STEAM-ACTUATED VALVE.

SPECIFICATION forming part of Letters Patent No. 358,804, dated March 1, 1887.

Application filed July 19, 1886. Serial No. 208,487. (No model.)

To all whom it may concern:

Be it known that I, FRANCIS ALBERT CRESSWELL, a citizen of the United States, residing at Strongstown, in the county of Indiana and State of Pennsylvania, have invented certain new and useful Improvements in Steam-Actuated Valves for Steam-Engines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a vertical longitudinal section. Fig. 2 is a transverse section on line $x-x$, Fig. 1.

This invention relates to improvements in the steam-actuated valves for reciprocating engines, having special reference to that class in which the main valve, moving in a separate cylinder, has the steam admitted alternately against each end of it by the motion of an auxiliary reciprocating valve, which alternately opens steam-ports communicating with the ends of the main valve-cylinders; and it consists in the construction and novel arrangement of parts, as hereinafter described, and pointed out in the claims.

Referring by letter to the accompanying drawings, A designates the steam-chest, M' the cylinder, M the piston, and m the piston-rod.

B is a cylindrical rotary valve reciprocating in a steam chamber or cylinder, the ends of which are indicated by the letters G H, as shown.

a is the point of junction of the steam-pipe from the boiler with steam-chest, and C D are inclined steam ways or passages through the rotary valve B, for conveying steam from the interior a' of the steam-chest to the respective rear and front ends of the cylinders, O and P being the steam-ports for said ends.

E is a cog-wheel on the rotary valve, standing in a recess or chamber, E', in the walls of the valve-cylinder, and F is a rack-bar, which passes through proper openings in the walls of said cylinder and meshes with the wheel E.

In the drawings the inclined steamway C is shown as opening into the port O, while the

similarly-inclined way D is cut off from the corresponding port P. Now, by moving the rack-bar so as to cause the cog-wheel to make one-half turn, the rotary valve will also turn, 55 and the inclinations of the steamways C D will be reversed, so that D will open into its port P, and C will be the cut-off from the port O, and the engine will be thus reversed.

j k are swinging gates or valves which open 60 and close the steam and exhaust ports. As shown in the drawings, the gate j permits steam to flow through the port O into the rear end of the cylinder, but prevents it from entering the exhaust-chamber I and escaping 65 thence through the exhaust tube or opening q. The gate k, however, cuts off steam, but allows the front end of the cylinder to exhaust through the tube or port R.

L is an auxiliary slide-valve moving in a 70 chamber between the cylinder and the exhaust-chamber, the shell of the latter forming its roof and that of the former its floor.

z and s are ports in the floor of the valve-chamber, situated at equal and suitable distances from the rear and front ends of the cylinder.

y and u are ports in the roof of the valve-chamber, not vertically above the respective ports z and s, but at equal and suitable distances outward from the same, or respectively toward the rear and front ends of the cylinder M'.

w w' are ports through the valve L, nearer together than the ports z and s, so that when 85 the ports w s communicate, as shown in the drawings, the port w' will be on the inner side of the port z.

x is the orifice of a tube or passage-way, x', which communicates with the end H of the 90 main valve chamber or cylinder, and c is the similar orifice of the tube or way, c', communicating with the end G of the same.

l l' are extensions or tappet-arms on the rear and front ends of the valve L.

The operation of the invention is as follows: The parts being in the position shown in Fig. 1, steam flows through the ports C and O into the cylinder M', driving the piston M outward. The steam opens the valve or gate j, as shown, 100 and pressing on the tappet-arm l slides the valve L, moving the valve or gate k outwardly,

so as to open the exhaust. The valve also moves sufficiently to cut off the ports *z* and *w* from each other, but allowing communication between the end *G* of the valve-cylinder and the exhaust-chamber *I*, and to bring the ports *s w* and orifice in line. When the piston passes the port *s*, the steam behind it escapes through the orifice *x* and pipe *x'* to the end *G* of the valve-cylinder, and moves the rotary valve *B* outward, so as to bring the steamways *D P* into communication, but cutting off the way *C* from the port *O*. The motion of the piston is then reversed, all the parts acting in the opposite direction in the manner described. The manner of reversing is heretofore explained. In double-cylindered engines, like locomotives, the rack-bar *F* may be made long enough to engage the cog-wheels on the cylindrical wheels of both cylinders in the described manner, so that both will be reversed simultaneously.

Having described this invention, what I claim, and desire to secure by Letters Patent, is—

1. The combination of the steam-chest, the cylindrical rotary valve having the steamways *C D* made through it, the valve-chamber forming at its ends steam-cylinders, of which the valve is the piston, the ports *O P*, the exhaust-chamber, the swinging gates *j k*, the piston and cylinder, and means, substantially as de-

scribed, to slide the rotary valve to reverse the motion of the piston when the same has nearly reached the end of its stroke in either direction, substantially as specified. 35

2. The combination of the steam-chest, the piston, the cylinder provided with the ports *O P*, the cylindrical rotary valve having the steamways *C D*, the valve-chamber *G H*, the exhaust-chamber *I*, the swinging gates thereof, the slide-valve *L*, having the extensions *l l'* and ports *w w'*, the ports *z s* in the floor and *y u* in the roof of the valve-chamber, and the pipes *c' x'*, having the orifices *c x*, and communicating with the ends *H G*, respectively, of the main valve-chamber, substantially as specified. 40 45

3. The combination of the steam-chest piston cylinder, having ports *O P*, exhaust-chamber *I*, and swing-gates *j k*, with the valve-chamber *G H*, cylindrical rotary valve *B*, provided with the inclined steamways *C D*, gear-wheel *E* on said rotary valve, and rack-bar *F*, engaging said gear-wheel to reverse the valve, substantially as specified. 50 55

In testimony whereof I affix my signature in presence of two witnesses.

FRANCIS ALBERT CRESSWELL.
